UNITED STATES PATENT OFFICE.

AUGUSTUS H. SELL, OF NEWARK, NEW JERSEY.

DESIGN FOR AN ARTICLE OF MANUFACTURE.

56,894.

Specification for Design.

Patented Jan. 4, 1921.

Application filed July 16, 1920. Serial No. 396,845. Term of patent 3½ years.

To all whom it may concern:

Be it known that I, AUGUSTUS H. SELL, a citizen of the United States, residing in the city of Newark, in the county of Essex and State of New Jersey, United States of America, have invented a new, original, and ornamental Design for an Article of Manufacture, of which the following is a specification, reference being had to the accompanying drawing, forming a part thereof, which shows my design as embodied in a badge, in which—

The figure is a front view of my new design for a campaign badge.

The design can be applied in numerous other articles; as for example, emblems, lapel buttons, stickpins, and watch charms.

What I claim and desire to secure by Letters Patent, is:

The ornamental design for an article of manufacture substantially as shown.

AUGUSTUS H. SELL.
